DIGITAL POWER SUPPLY

Robert E. C. Smyth, Centerport, N.Y., assignor to Digital Apparatus Corporation, Deer Park, N.Y.

Filed Jan. 12, 1970, Ser. No. 20,873

Term of patent 14 years

Int. Cl. D13—02

U.S. Cl. D26—15

Fig. 1

Fig. 2

Fig. 3

FIG. 4

FIG. 5

FIG. 6

FIG. 7

FIG. 1 is a perspective view of a digital power supply showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and

FIG. 7 is a bottom plan view thereof.

The broken lines are shown for illustrative purposes only and form no part of the claimed design.

I claim:

The ornamental design for a digital power supply, substantially as shown and described.
